STAKE PULLER

Jack E. Majors, Santa Cruz, Calif.

Application June 14, 1957, Serial No. 665,867

4 Claims. (Cl. 254—132)

The present invention relates to improvements in a stake puller; and it consists of the combinations, constructions and arrangement of parts, as hereinafter described and claimed.

The usual way to remove stakes that are driven into the ground to hold concrete forms in place is to take a heavy hammer, railroad pick or wrecking bar, and beat and pry upon the stake until it comes free from the ground. This method is not only make-shift and dangerous, but it soon converts an otherwise orderly group of workmen into a confused group of men that interfere with each other.

An object of my invention is to provide a hand-operated stake puller that has a U-shaped bite bar, or stake-gripping member, pivoted to the short arm of a lever-handle and designed to grip and lift a stake when the lever-handle is swung in one direction, and to slide downwardly on the stake into a new position when the lever-handle is swung in the opposite direction. The lever-handle fulcrums on a pedestal that in turn rests on top of the concrete foundation, when an operator uses the stake puller to remove stakes that have been used to hold wooden foundation forms in place.

A further object of my invention is to provide a stake puller of the type described, which is simple in construction, durable and efficient for the purpose intended. The device can be made of different sizes for pulling stakes that vary in cross-sectional area.

Other objects and advantages will appear as the specification proceeds, and the novel features will be set forth in the appended claims.

Drawing

For a better understanding of the invention, reference should be had to the accompanying drawing, forming part of this specification, in which:

Figure 1 is a side elevation of the stake puller, shown on a small scale, and illustrating how it can be used for pulling a stake from the ground;

Figure 2 is a plan view of a part of the stake puller and illustrates in full size the U-shaped bite, a portion of the lever-handle, and a top plan of the cylindrical pedestal that is welded to the lever-handle; and

Figure 3 is a side elevation of Figure 2 and shows the fulcrum-pedestal resting on top of a concrete foundation, and the U-shaped bite, gripping the stake, preparatory to lifting the stake when the lever-handle is swung in a counter-clockwise direction on its fulcrum pedestal.

While I have shown only the preferred form of my invention, it should be understood that various changes, or modifications, may be made within the scope of the annexed claims without departing from the spirit thereof.

Description

In carrying out my invention, I provide a lever-handle A, that is elongated as shown in Figure 1, and has a cylindrical-shaped pedestal B welded thereto at 1. I do not wish to be limited to any particular size of lever-

2

handle, but I have found that if it is 27½" long and ¾" wide, and made of tool steel rod, a serviceable strong handle will be the result. The lever-handle may be hexagonal in cross-section and preferably has a cant of 29° occurring about 3¼" from the end of the short arm A¹ to the cylindrical pedestal B.

The pedestal B is welded to the underside of the lever-handle A, as shown at 1, and the short arm A¹ of the lever-handle, is curved in the manner shown in Figures 1 and 3. A more satisfactory working performance of the tool results when the short arm A¹ of the lever-handle A is curved in this manner. The hand-grip end of the lever-handle A is provided with a nail-claw end A² (see Figure 1) so that the tool may be reversed, and the nail-claw end used for removing nails and spikes.

Figure 2 shows a U-shaped steel bite C, or stake-gripping member, that has two parallel sides 2 and 3, and an interconnecting transverse portion 4. The side 2 carries a pair of downwardly-extending integral ears 5 and 6, which are spaced from each other, and have aligned openings 7 and 8 therein. The short arm A¹ of the lever-handle is reduced in width at its lower end and is provided with a transverse bore 9 of the same diameter as the openings or bores 7 and 8, and is aligned with these bores. A pivot bolt D has its shank passed through the aligned bores 7, 9 and 8, and in this way the steel bite C is pivoted to the lever-handle A. The stake-gripping member C, when in stake-engaging position, lies in a slightly inclined plane with the side 2 being disposed above the pivot bolt D. Therefore, the member C will tend to swing in a clockwise direction.

The side 2 of the steel bite C has an inner edge 2a that makes an obtuse angle with the upper surface 2b of this side. A jaw E, angle-shaped in cross-section, is removably secured to the top surface 2b of the side 2, by cap screws 9, or other suitable fastening means. The jaw E has a length equal to the length of the side 2, and the jaw has an angled portion E¹ that covers the inner edge 2a throughout its length. The outer surface of the portion E¹ has longitudinally-extending teeth 10 formed therein. The teeth are shaped for permitting the steel bite to slide downwardly over a stake F, but to frictionally engage with the stake for lifting it when the steel bite C is moved upwardly. At the same time, the lower inner corner edge 11 of the side 3 will frictionally grip the opposite side of the stake F from that engaged by the teeth 10. Practically all of the teeth 10 will engage with the stake side due to the angle made by the portion E¹ of the jaw.

Operation

In Figure 1, I show an outer form G and an inner form H, for receiving concrete therebetween that provides a concrete foundation J. A stake F is illustrated as being driven into the ground K for holding the outer form G in place. After the concrete foundation has set, it is necessary to remove the stakes F.

I show the stake puller with its steel bite C slipped down over that portion of the stake F that projects above the top of the outer form G. The fulcrum-pedestal B rests on the upper surface 12 of the concrete foundation J. A downward swinging of the long arm of the lever-handle A, about the fulcrum-pedestal B, will cause the short arm A¹ to lift the steel bite C. The steel bite C, when engaging with the stake F, is positioned above the pivot bolt D, and will tend to rock in a clockwise direction about the pivot bolt D, as the bite is lifted, and this will cause the jaw E and the corner 11 to grip opposite sides of the stake with sufficient force to prevent the bite C from slipping upwardly on the stake. The result will be a vertical lifting of the stake F. The fulcrum-pedestal

B may slide slightly over the surface 12 during this movement.

If the stake F is not freed from the ground on this first upward pull of the stake-gripping member, the operator then swings the lever-handle A in the opposite direction. This will slide the steel bite C downwardly on the stake F into a new position. The first operation on the lever-handle A is then repeated for lifting the stake an additional distance. A repeated swinging of the lever-handle A, in both directions, will gradually work the stake F out of the ground until it is freed. The teeth 16 of the jaw E are provided primarily for pulling metal stakes out of the ground. Stakes made of wood-iron or steel can be gripped by my stake puller and quickly and easily removed from the ground.

The U-shaped stake-gripping member C will have its inner side 2 positioned above the pivot bolt D, when the member receives a stake F. This will cause the outer side 3 to substantially lie in a horizontal plane that extends through the axis of the pivot bolt D; and, therefore, the member C will tend to swing downwardly into a stake-gripping position as soon as the member starts moving upwardly.

It will be seen from Figure 3 that the axis of the cylindrical-shaped fulcrum-pedestal B is disposed at a higher elevation than the axis of the pivot bolt D, when the lever-handle is in a normal upwardly-inclined position at the beginning of a downward stroke for pulling the stake F out of the ground. The curve in the short lever arm A¹ will dispose the pivot bolt D slightly below the axis of the fulcrum-pedestal B. The inner side 2 of the U-shaped stake-gripping member C will be disposed substantially in the same horizontal plane that extends through the pedestal axis, when the member grips a stake F. Therefore, a downward rocking of the longer lever arm will exert the greatest upward lift on the member C. It will be seen that when the fulcrum-pedestal B rests on the upper surface 12 of the concrete foundation J, both the pivot bolt D and the stake-gripping member C will be disposed a slight distance above the surface 12 when the member receives a stake F. Therefore, the stake can be gripped effectively, even though its upper end projects only slightly above the concrete foundation.

The pedestal B has a cylindrical outer surface concentric with an axis extending transverse the lever handle. Further, the stake gripping member is connected to the lever handle by a single pivot only. A series of levers and pivots as known in the prior art has been dispensed with to obvious advantage in the functioning of the stake puller. Connection of the puller to the stake is rendered much easier since it is only necessary to control one freely pivotal member in making the connection. It is further to be noted that the pedestal's surface constitutes a rocking base on this unitary fixed portion of the lever handle and does not comprise relatively moving parts. This not only simplifies construction and operation, but general handling of the puller. It is obviously simpler, can be placed in trucks or pulled out of the trucks for use much easier, setup time is substantially eliminated, and further, obviously manufacturing costs are greatly reduced as compared with heretofore known pullers. The rocking base formed by the pedestal permits the free rocking of the lever handle on any supporting portion adjacent the stake and also permits the movement of the fulcrum toward the stake as the latter is pulled upwardly.

I claim:

1. A stake puller comprising a lever handle, said lever

handle having a long lever arm and a short lever arm and a fulcrum, said fulcrum comprising a member attached to the bottom of said lever handle, said lever handle having a longitudinal axis, said fulcrum member having a lower cylindrical surface formed concentric with an axis extending transversely with respect to said axis of said lever handle, said cylindrical surface being positioned under the lever handle and adapted to contact a supporting surface adjacent a post to be pulled and being freely slideable over said surface, a single pivot means mounted in the short lever arm and forming a fixed axis, and a stake gripping member directly connected to said lever handle by said pivot means, said stake gripping member comprising a pair of spaced sides extending substantially at right angles to the longitudinal axis of the lever handle, said cylindrical surface forming a rocking base for said puller for rocking of said lever handle thereon to raise a post engaged with said gripper member, said pivot means axis being positioned above said longitudinal axis of said lever handle and the center of rotation of said cylindrical surface being positioned below the longitudinal axis, the relationship between said center of rotation and the first mentioned axis being such that when said cylindrical surface is in contact with a horizontal surface and said handle is rotated upward with respect thereto the fixed axis will lie below the horizontal plane containing said center of rotation of said cylindrical surface when the handle has been moved to its maximum upward position and the end of the stake puller opposite said long lever arm contacts the said surface.

2. The combination of claim 1 in which the short lever arm is curved upwardly from a point on the lever handle disposed adjacent to the fulcrum.

3. The combination of claim 1 including said stake gripping member having a pair of depending ears, said ears being connected to said lever handle by said pivot means and said stake gripping member being above said ears.

4. A stake puller comprising a lever handle, said lever handle having a long lever arm and a short lever arm and a fulcrum, said fulcrum comprising a member attached to the bottom of said handle, said fulcrum having a lower cylindrical surface formed concentric with an axis extending transversely with respect to the lever handle, said short lever arm being canted with respect to said long lever arm with the end of said short lever arm being positioned to the opposite side of said handle with respect to said fulcrum and to one side of said long lever arm, pivot means fixed in said end of said short lever arm, a stake gripping member directly connected to said lever handle by said pivot means, said stake gripping member comprising an element adapted to grasp a post received within said gripping member, said stake gripping member further comprising a pair of integral ear members extending downwardly from said stake gripping member along one side thereof, said stake gripping member ears having means pivotally connecting said stake gripping member to said pivot means at a point spaced beneath one side of said stake gripping member.
